(57) **CLAIM**

The ornamental design for a nail gel curing lamp, as shown and described.

DESCRIPTION

FIG. 1 is a perspective view of a nail gel curing lamp showing our new design;

FIG. 2 is a top view thereof;

FIG. 3 is a bottom view thereof;

FIG. 4 is a front side view thereof;

FIG. 5 is a back side view thereof;

FIG. 6 is a right side view thereof;

FIG. 7 is a left side view thereof; and,

FIG. 8 is a perspective view of the nail gel curing lamp in use.

In FIGS. 1-8 the broken lines define portions of the nail gel curing lamp that form no part of the claimed design. In FIG. 8 the broken line illustration of the hand shows the environment of use and forms no part of the claimed design.

1 Claim, 5 Drawing Sheets
